VALVE ACTUATING MECHANISM

Louis R. Spencer, West Hartford, Conn., assignor to Spencer Aircraft Motors, Inc., Hartford, Conn., a corporation of Connecticut

Application June 7, 1938, Serial No. 212,346

4 Claims. (Cl. 123—90)

This invention relates to improvements in actuating mechanisms for the valves of internal combustion engines.

One object of the invention is to provide a valve-actuating mechanism of simple construction in which adjustments can be readily made for purposes of providing proper clearances or for compensating for wear.

A further object of the invention is to provide a valve-actuating mechanism comprising a rocker arm or lever carrying a valve-stem-engaging member but with which a series of members may be interchangeably used, the several members being of different sizes to compensate for wear or to provide proper adjustment of the mechanism with respect to the valve stem and the cam or other operating element by which the arm or lever is rocked.

A still further object of the invention is to provide a valve-actuating mechanism comprising a valve-stem-engaging member securely attached to its rocker arm or lever, but from which arm or lever the member may be readily removed to permit replacement thereof with a new valve-stem-engaging member.

Another object is the provision of a valve-stem-actuating mechanism in which the moving parts are efficiently lubricated.

More specifically, the invention contemplates a valve-actuating mechanism comprising a rocker arm or lever carrying the valve-stem-engaging member, said member consisting of a substantially circular disc-like element seated in a recess in the rocker arm, the size and shape of said member and recess being such that a major portion of the periphery of the disc is embraced within the recess. In other words, the walls of the recess extend around more than half of the disc and the diameter of the disc is greater than the length of the entrance to the recess, so that, normally, the disc is securely held in the rocker arm. However, a portion of the periphery of the disc is flattened to form a valve-stem-engaging surface and, by rotating the disc in the recess to position the portion with the reduced over-all dimension in the entrance to the recess, the disc can be readily removed.

With these and other objects in view, the invention consists in certain details of construction and combinations and arrangements of parts, all as will hereinafter be more fully described, and the novel features thereof particularly pointed out in the appended claims.

In the accompanying drawing—

Figure 1 is a vertical sectional view taken lon-

gitudinally of the valve stem, but showing the stem and rocker arm or lever in elevation;

Fig. 2 is a similar view, but somewhat enlarged, showing the rocker arm and valve stem in their depressed positions, in dotted lines;

Fig. 3 is a bottom plan view of the rocker arm and valve-stem-engaging member, this view being taken in the plane indicated by the line 3—3 of Fig. 2;

Fig. 4 is a transverse sectional view on the line 4—4 of Fig. 2; and

Figs. 5 and 6 are elevational views illustrating different sizes of valve-stem-engaging members.

Only the upper portion of the casing 10 is illustrated and, as the latter does not form any part of the present invention, a detailed description of the same is unnecessary. As is customary in structures of the present type, the valve stem 11 is yieldingly urged upward by one or more coiled springs 12 surrounding the same and engaging against the under surface of an enlargement 13 mounted on the upper end of the valve stem. The valve stem is illustrated in Fig. 1 in its upper position, this being the position occupied by the stem when the valve is closed. To depress and open the valves in proper timed relation with one another and with respect to the ignition system, a cam shaft 14 provided with a series of cams 15 is revolubly supported in the upper portion of the casing. Each cam 15 is adapted to engage and depress a rocker arm or lever 16 which, in turn, is adapted to depress valve stem 11, said arm or lever 16 being provided with what, for convenience, has been termed a valve-stem-engaging member 17.

In order to facilitate the interchangeable use of a number of different-sized valve-stem-engaging members, a feature that is desirable in connection with the proper original adjustment, so to speak, of the rocker arm with respect to the valve stem, and in connection with replacement of worn valve-stem-engaging members, the present construction embodies a valve-stem-engaging member that may be readily removed and replaced while, at the same time, it is firmly retained in proper operating position during normal operating conditions. Preferably, each of the valve-stem-engaging members 17 is of disc-like formation and substantially circular, except for a portion of its periphery which is flattened as at 18, this flattened portion being adapted to engage against the flat upper end face of the valve stem 11. By reason of the formation of the flattened surface 18, each member 17 might be said to have a major and a minor over-all di-

mension, the minor dimension being the distance between the flat surface 18 and a diametrically opposite point on the periphery of the disc, while the major dimension will be the normal diameter 5 of the disc or the distance between diametrically opposite points on the periphery of the disc in a line parallel to the flat face 18. It should also be here noted that, while the diameters of the circular portions of the discs are identical, nevertheless the several discs of a series can be of 10 different minor dimensions by removing varying quantities of metal from the individual discs in forming the flattened surface 18. Thus a series of these graduated discs can be used to compensate for differences caused by wear either on 15 the cams 15 or on the end of the valve stem 11.

For securing the valve-stem-engaging member in the rocker arm or lever 16, the latter is formed at its free end with a recess of a shape corresponding to and adapted to receive and embrace a major portion of the circular section of the disc 17. By having the recess accommodate a greater portion of the disc, so that the walls of the recess extend more than half way around 25 the disc, the latter, while in such a position, cannot be removed from the recess. However, as will be appreciated, the entrance to the recess is at least as large lengthwise as the minor dimension of the disc so that, if a disc is turned to a 30 position where its minor dimension is in registry with the entrance to the recess, the disc can be slipped into the recess and, then, by rotating the disc in the recess, the flattened surface can be moved around until it is located exteriorly of the 35 arm in a plane parallel to the end face of the valve stem. To prevent accidental rotation of the disc in the rocker arm recess, a cross-pin 19 is preferably provided. In other words, with the pin 19 inserted, the disc cannot be rotated 40 but, by removing the pin 19 from the disc and arm, the disc may then be rotated to again position the minor dimension of the disc in the entrance to the recess, whereby the disc can be removed and a new disc inserted to compensate 45 for any adjustments that might be necessary.

In order to accommodate any relative movements between the disc 17 and the arm 16, the pin 19 preferably fits somewhat loosely in the disc, so as to permit a rocking movement of the disc. Thus, movement of the arm up and down, 50 as indicated by the dotted lines in Fig. 2, does not interfere with the flat seating of the surface 18 on the surface of the valve stem, nor does it effect any substantial relative movement between the contacting surfaces of the disc and valve stem. Consequently, wear at this point is 55 reduced to a minimum. Preferably, means are also provided for lubricating the surface of the disc 17 in contact with the wall of the recess in the arm 16. For instance, the cam shaft 14 may be provided with an axial bore 20 serving the purpose of a lubricant reservoir, from which lubricant may escape through a duct 21 in said cam shaft once each revolution of the shaft, this flow 60 of lubricant occurring when the duct 21 extends downwardly in moving into and out of contact with the upper surface of the arm 16. Likewise, arm 16 is provided with a duct 22 located in alinement with a duct 21, so that each time the duct 21 passes over the duct 22, a small quantity 65 of lubricant will be fed down into the interior of the recess in the arm where it will flow between the contacting surfaces of the recess and disc.

As previously explained, the discs in any given 70 series of discs will be of different sizes so far

as concerns the distance between the flat surface 18 and the diametrically opposite point on the disc, so that in the original installation of a disc, the proper-sized disc can be used to permit proper seating of the valve when the latter is in 5 closed position. Due to the ease with which discs can be slipped into and out of the recesses in the arm, one or more discs can be readily placed in the arm until the proper adjustment 10 of the valve stem and valve is obtained. Likewise, when undue wear has occurred and it becomes necessary or desirable to replace a disc, it is a very easy matter to remove a disc then in the arm and replace it with another disc of the proper size. It might be added, although it will 15 be readily appreciated, that this removal and replacement of discs in an arm does not involve any deformation of the material of which the arm is made. That is, there is no necessity of upsetting or spinning over the material at the 20 entrance of the recess in securing a disc in the arm and, hence, the replacement of discs does not entail destruction or deformation of any part 25 of the arm.

What I claim is:

1. A valve-actuating mechanism comprising a rocker arm and a valve-stem-engaging member carried thereby, said arm having a recess therein formed with an elongated entrance, the length of 30 said entrance being less than that of the interior of the recess, and said member being of disc-like formation but formed with a major and a minor over-all dimension, the minor dimension of said member corresponding to the length of the entrance to said recess, and said member being 35 rotatable in said recess to position said member with the minor dimension thereof in registry with said entrance whereby said member can be removed from said recess, and a removable locking pin engaging the member for permitting only 40 oscillatory motion of said member in said recess.

2. A valve-actuating mechanism comprising a rocker arm having a recess therein and a valve-stem-engaging member of substantially circular disc-like formation, the major portion of said disc 45 being embraced by but rotatable in said recess, and a locking pin extending into said recess permitting only oscillatory motion of the disc in said recess, said disc being removable edgewise from the recess in the absence of said pin.

3. A valve-actuating mechanism comprising a rocker arm having a recess therein and a valve-stem-engaging member of substantially circular disc-like formation, the major portion of 50 said disc being embraced by but rotatable in said recess, said disc having major and minor over-all dimensions with the minor dimension substantially corresponding to the entrance of said recess in the arm, whereby rotary motion of the disc to position the same with its minor dimension in registry with said entrance will permit removal of the disc edgewise from said recess, and a removable retaining pin extending through the arm and disc normally permitting 55 only oscillatory motion of the disc.

4. A valve-actuating mechanism comprising a rocker arm having a recess therein and a valve-stem-engaging member of substantially circular disc-like formation, the major portion of said disc being seated in and embraced by said recess, 60 said disc being rotatable in said recess for removal edgewise therefrom, and a pin extending through said arm and disc, said disc being capable of a rocking motion on said pin.
